DESIGN FOR AN OIL BAR

Francis Lawrence Ayres, Chicago, Ill., assignor to Stewart-Warner Corporation, Chicago, Ill., a corporation of Virginia

Application February 18, 1946, Serial No. 126,669

Term of patent 14 years

(CL. D52—2)

To all whom it may concern:

Be it known that I, Francis Lawrence Ayres, a citizen of the United States, residing at Chicago, in the county of Cook and State of Illinois, have invented a new, original, and ornamental Design for an Oil Bar, of which the following is a specification, reference being had to the accompanying drawing, forming part thereof.

The figure is a perspective view of an oil bar, showing my new design. The side of the bar not shown in the drawing is plain.

I claim:

The ornamental design for an oil bar, substantially as shown and described.

FRANCIS LAWRENCE AYRES.
